UNITED STATES PATENT OFFICE.

ALBERT OSTROM, OF ELKHART, INDIANA.

DESIGN FOR A MILK-BOTTLE HOLDER AND TICKET-RACK.

50,975.

Specification for Design. Patented June 26, 1917.

Application filed March 26, 1917. Serial No. 157,569. Term of patent 7 years.

To all whom it may concern:

Be it known that I, ALBERT OSTROM, a citizen of the United States, residing at Elkhart, in the county of Elkhart and State of Indiana, have invented a new, original, and ornamental Design for Milk-Bottle Holders and Ticket-Racks, of which the following is a specification, reference being had to the accompanying drawings, forming part thereof.

The figure is a view in elevation of a milk

bottle holder and ticket rack, showing my new design.

I claim:

The ornamental design for a milk bottle holder and ticket rack, as shown.

ALBERT OSTROM.
